UNITED STATES PATENT OFFICE.

ERNEST JAMES SMITH, OF LONDON, ENGLAND, ASSIGNOR TO THE GOSS PRINTING PRESS COMPANY, OF CHICAGO, ILLINOIS, A CORPORATION OF ILLINOIS.

MATRIX-FORMING MACHINERY.

Application filed February 7, 1927. Serial No. 166,330.

My invention relates to matrix forming machinery and has for its object the provision of a new and improved form and arrangement of parts for holding a matrix under heavy pressure in contact with the type or other form upon which the matrix has been pressed, such maintenance under heavy pressure to continue preferably during the drying operation. It is one of the objects of my invention to provide a construction of this type of such power that it can be utilized to advantage for pressing a dry flong or a substantially dry flong into the form for cutting the matrix, drying means being preferably provided in the cutting press for quickly completing the matrix.

It is one of the objects of my invention to provide improved means in a device of this type for applying the pressure whereby the platen by which the pressure is applied may be given a quick preliminary movement into position for the application of the final operative pressure thereto. It is one of the objects of my invention to provide for this by the use of mechanically operating power means for the preliminary movement of the platen and hydraulic press means for the comparatively much heavier pressure at the end of the operative movement. To this end, it is one of the objects of my invention to provide a construction and arrangement by which the platen may be free to move under the influence of the mechanically applied power and by which the application of the heavier power hydraulically may be effected promptly at the desired time and may be stopped promptly when the pressure has reached the predetermined desired maximum.

It is another object of my invention to provide automatically acting control means by which the pressure upon the platen may be kept at the predetermined maximum for any desired length of time. For accomplishing this result, it is one of the objects of my invention to provide pressure controlled means for regulating the application of power, this being brought about preferably by the use of pressure actuated means for controlling the supply of current to an electric motor by which the pressure means is operated.

It is another object of my invention to provide a construction of the type above referred to in which the withdrawal of the pressure from the matrix may be effected expeditiously in such a manner as to leave the mechanism

ready for another pressing operation promptly upon the withdrawal of the completed matrix and the substitution of another.

It is still another object of my invention to improve machines of this type in sundry details hereinafter pointed out. The preferred means by which I have accomplished my several objects are illustrated in the drawings and are hereinafter specifically described. What I consider as my invention and desire to cover by Letters Patent is set forth in the claims.

In the drawings—

Fig. 1 is a side view of the preferred form of my machine, shown more or less diagrammatically, and with certain of the parts broken away for better illustrating the construction, a part thereof being substantially a section at line 1—1 of Fig. 4.

Fig. 2 is a transverse vertical section 75 through the upper portion of the machine at one side thereof.

Fig. 3 is a horizontal section taken at line 3—3 of Fig. 2.

Fig. 4 is a front view of my improved machine, with the operating rod shown in section and with the bracket for such rod removed.

Fig. 5 is a detail view showing a portion of the parts as illustrated in Fig. 1 but with the parts in a changed position.

Fig. 6 is a view similar to Fig. 1 but showing a modified form of construction; and

Fig. 7 is a vertical cross section through the transverse power shaft at the top of the machine.

Referring now to Figs. 1 to 5 inclusive, in which corresponding parts are indicated by the same reference characters, 15 indicates the base of my machine which in the construction shown comprises two parts, one of such base parts being formed integrally with a cylinder 16 rising therefrom with lugs 17 extending from its sides at the top for supporting the main standards 18. Within the cylinder 16 there is mounted a piston 19 carrying on its upper end a platen 20 which is slidably mounted upon the standards 18 so as to be movable up and down thereon with the piston. The platen 20 is provided on its front face 105 with an extension 21 which is adapted to serve as a work table.

Mounted upon the upper end portions of the standards 18 and held rigidly in position thereon, there is a heavy platen 22 toward and 110

from which the platen 20 is movable as herein-after described for pressing between the platens the part 23 comprising a form and a flong in contact with the form on its top face. 5 For heating the platen 20, it is cored out, as indicated at 24, a pipe 25 being connected therewith for feeding steam thereto from any suitable source.

In the use of my machine, a form is placed 10 in position upon the table 21 with a flong or a partially formed matrix in contact with the form. The form and flong are then pushed into position between the platens 20 and 22 and the mechanism is operated for 15 moving the platen 20 upwardly for forcing the form into the flong, or for applying pressure from the form to the flong or partially cut matrix if it has already been subjected to pressure. In my improved machine as 20 hereinafter described, the initial operation of the machine serves to press the platen 20 upward very quickly into approximately its final operative position, and then a very heavy 25 power, acting at a correspondingly slower rate, is applied for attaining the desired degree of pressure between the form and the matrix. The platen 20 is held in its elevated position for effecting this pressure for the desired period for completely drying the 30 matrix, whereupon the platen 20 is again moved downwardly and the matrix removed.

The means provided in the construction shown in Figs. 1 to 5 for moving the platen 20 upwardly for pressing the form between the platen 20 and the platen 22 comprises a transverse shaft 26 mounted in bearings carried by standards 27 rising from the platen 22, as is best shown in Fig. 4. This shaft is driven by a worm gear 28 which in turn is 35 driven by a worm 29 mounted upon a longitudinally extending drive shaft 30. As is clearly shown in Figs. 2 and 3, the shaft 30 is mounted in suitable bearings in a trough-like device 31 which is equipped with anti-friction bearing devices 32 at opposite ends of the worm 29 for taking the end thrust. Upon its outer end, the shaft 30 is provided with a sprocket gear 33 connected by means 40 of a sprocket chain 34 with a sprocket pinion 35 mounted upon the drive shaft of an electric motor 36 carried by the platen 22. The arrangement is such that upon the rotation of the motor 36 the shaft 26 is driven at a comparatively much slower speed of rotation. 45

The electrical connections for feeding electrical energy to the motor 36 for operating it comprise lead wires 37 which connect the motor 36 in series with a switch 38 of 50 any approved type adapted to be operated by an arm 39. In the construction shown, the switch is designed to be open when the arm 39 is moved toward the left in the position as shown in Fig. 1 and is closed for operation 55 of the motor when the arm 39 is moved to-

ward the right in any approved manner. The means for operating the arm 39 for opening and closing the switch 38 comprises an operating rod 40 slidably mounted in bearings 41 rising from the platen 22. The rod 40 is flexibly connected with the arm 39 of the switch 38 by any suitable mechanism so that when the rod 40 is moved toward the right in Fig. 1 the arm 39 is given an operative stroke for closing the switch and so that 75 when the rod 40 is moved toward the left in said figure the switch 38 is opened. The rod 40 is given its operative movements through the medium of a bell-crank lever 42, one arm of which is in the form of a handle and the other arm of which is connected with the operating rod 40 by means of a link 43. In the construction shown the bell-crank lever 42 is pivotally mounted upon a bracket or arm 44 extending forwardly from the platen 22 80 for convenient actuation by an operator standing in front of the machine. A coiled spring 45 is mounted on the rod 40, bearing at one end against the standard 41 and bearing at its other end against the collar 46 85 forming a part of the means for connecting the arm 39 of the switch with the rod 40. The movement of the rod 40 toward the right for closing the switch must accordingly be effected against the action of the spring 45, 90 and this spring is adapted to move the rod toward the left for opening the switch when conditions are such as to permit such movement. 95

In the construction shown, the platen 20 is 100 moved upwardly upon a half rotation of the shaft 26 and is moved downwardly upon the succeeding half rotation of said shaft, means being provided for automatically throwing the mechanism out of operation at the end of 105 each succeeding half rotation. This means comprises a cam 47 fixedly mounted upon the shaft 26 in position to bear upon a transversely extending arm 48 carried by a sleeve 49 revolvably mounted upon the operating 110 rod 40. The sleeve 49 is also provided with a downwardly extending arm 50 which stands in contact with a lug 51 mounted upon the platen 22 directly underneath the operating rod 40. The arrangement is such that upon the rotation of the shaft 26 in clockwise direction in Fig. 1, the cam 47 serves to move the arm 48 downwardly for carrying the arm 50 toward the left in Fig. 2 from the position shown in dotted lines therein to the position shown in solid lines. When the arm 50 is standing in the position shown in dotted lines in Fig. 2, the shaft is held from movement toward the left in Fig. 1. When, however, the arm 50 is caused to clear the lug 51, the spring 45 acts promptly to move the rod 40 toward the left in said Fig. 1 for opening the switch 38 whereupon the rotation of the parts is promptly stopped. For effecting this prompt stoppage of the shaft 120 125 130

26 and its connected parts upon the opening of the switch 38, I have provided a brake mechanism 52 of any approved form operated by an arm 53 which has a suitable flexible connection with the operating rod 40 (see Fig. 1) so that upon movement of the rod 40 toward the left in said Fig. 1 the brake is applied to the shaft 26.

With the parts in the position as shown in Fig. 1, when it is desired to give the shaft 26 a half rotation from the position as there shown, the handle of the lever 42 will be moved downwardly against the action of the spring 45 serving to close the switch 38, to release the brake 52, and to move the arms 48 and 50 toward the right so that the arm 48 can engage the flat face of the cam 47 and the arm 50 can engage the end face of the lug 51, as is best shown in Fig. 5. As will be readily understood when the bell-crank lever 42 is then released the rod 40 is held from movement toward the left in said Fig. 1 until the shaft 26 has completed a half rotation in clockwise direction in said figure, at which time the cam 47 serves to release the arm 50 from the lug 51.

The cam 47 is so arranged upon the shaft 26 as to stop the rotation of the shaft at the time when the platen 20 has been moved upwardly by the shaft to the limit of its movement. The means provided for moving the platen 20 upwardly by power from the shaft 26 comprises eccentrics 54 at opposite sides of the machine connected by means of links 55 with the platen. As is best shown in Fig. 1, the lower end of each of the links 44 is in the form of a loop within which a bearing block 56 is slidably mounted, such block being journaled upon a pin 57 mounted in the platen 20. A spring 58 is mounted in each of the links below the slide block 56, serving as the means for applying the pressure from the link 55 to the platen 20 through the pin and slide block. By the use of this means, when the shaft 26 is given its operative half rotation for carrying the platen 20 upwardly, the pressure is applied satisfactorily to the platen through the spring 58 regardless of any slight variations in the thickness of the form 23 being worked upon. In the arrangement described, the shaft 26 is designed to be given its operative half rotation in a comparatively very short time for effecting the initial movement of the platen 20, such movement preferably to consume not more than two or three seconds.

The means for applying the final comparatively much greater effective pressure upon the platen 20 comprises means for forcing oil or other pressure fluid into the cylinder underneath the piston 19. This means comprises an oil tank 59 which is connected with the cylinder 16 by means of a line of piping 60, such line of piping 60 having an oil pump 61 interposed therein for forcing oil from the

tank 59 through a pipe 62 into the cylinder. In the construction shown the pump 61 is driven by means of suitable gearing from an electric motor 63. This motor is connected with any suitable source of electrical energy 70 by means of line wires 64, such wires serving to connect the motor in series with a switch 65 and a switch 66. The switch 66 is designed to be of any suitable type comprising an operating arm 67 so arranged that the switch is closed when the arm is standing in the position as shown in Fig. 1 and is open when the arm 67 is given a downward stroke from the position shown in said figure. The arm 67 of the switch extends in the construction shown between lugs 68 carried by one of the links 55, being so arranged that upon the upward movement of the link 55 the arm 67 is moved for closing the switch and that upon the downward movement of the link 55 the arm 67 is moved for opening the switch. By reason of this arrangement, the motor 63 is automatically thrown into operation upon the upward movement of the link 55 and is automatically thrown out of operation upon the downward movement of such link. The motor 63 is thus caused to begin operation before the end of the initial upward movement of the platen 20 and is thrown out of operation before the end of the downward movement of the platen 20.

The switch 65 may also serve for stopping the operation of the motor 63 independently of the movement of the link 55. This switch is connected by means of a stem 69 with a pressure device which has direct connection with the interior of the cylinder 16. In the construction shown the pressure device comprises a casing 70 connected by means of a pipe 71 with the pipe 60. The stem 69 extends into the casing 70 through a suitable stuffing box 72, being connected at its inner end with a piston 73 which is moved downwardly by the internal pressure against the action of a spring 74, means being preferably 100 provided for regulating the tension of the spring 74 for controlling the pressure at which the switch 65 is opened. As will be readily understood when the pressure within the cylinder 16 caused by the action of the pump 61 is brought to the maximum pressure desired, the switch 65 is opened against the action of the spring 74 and the motor 63 and pump 61 are thrown out of operation. When thereafter the pressure within the cylinder 16 decreases, the spring 74 again forces the piston 73 upwardly for closing the switch 65 and thus causing the motor and pump again to operate.

Means is also provided in connection with the pump 61 and the cylinder 16 for controlling the delivery of the fluid under pressure to the cylinder independently of the operation of the pump. This means comprises a line of piping 75 serving as a by-pass from 125

the cylinder 16 to the tank 59. By the use of the pipe 75 the oil is permitted to pass directly from the cylinder 16 to the tank independently of the pump 61, and the oil forced toward the left in Fig. 1 by the pump 61 through the pipe 60 is also permitted to return to the tank 59 without being forced into the cylinder 16. For closing the pipe 75 so as to force the oil from the pump 61 into the cylinder, a valve 76 is interposed in the pipe 75, the stem 77 of the valve being controlled by a rod 78 which has a telescopic connection with the stem. A spring 79 surrounding the rod 78 and the stem 77 serves to press the stem yieldingly into closing position when the rod is moved downwardly. When the valve 76 is thus closed, the oil from the pump 61 is forced into the cylinder 16 beneath the piston 19 serving to force the platen 20 upwardly.

The means for operating the valve 76 through the medium of the rod 78 comprises in the construction shown a cam 80 mounted on the shaft 26 adapted by engagement with a roller 81 carried by the rod to force the rod down quickly at the end of the half rotation into the position as shown in Figs. 2 and 4. For effecting a quick return of the rod to its uppermost position for opening the valve 76 at the start of the half rotation of the shaft 26 from the position shown in said Figs. 2 and 4, a spring 81^a is provided bearing on the rod and on a bearing 81^b in which the rod is slidably mounted. The arrangement is such that the valve 76 is closed just as the movement of the platen 20 by the mechanical means ends, ready for the movement of such platen by the hydraulic means. As is clearly shown in Fig. 4, there is preferably a lost motion connection between the stem 77 and the rod 78 by the use of a pin 77^a and a slot 77^b so that as the rod 78 is raised by the spring 81^a the stem 77 is carried upwardly therewith.

By the provision of the mechanism just described, the effective action of the pump 61 is controlled with respect to the movement of the platen 20. When the motor 36 is thrown into operation through the use of the bell-crank lever 42, as soon as the link 55 is drawn upwardly a short distance the switch 66 is closed for starting the motor 63. The pump 61 then starts to operate, drawing oil from the tank 59 and forcing it toward the left in Fig. 1. The piston 19 is then drawn upward mechanically through the medium of the links 55 independently of any hydraulic pressure within the cylinder 16, the oil being adapted to enter the cylinder 16 through the pipe 75 and the open valve 76 independently of the pump 61. As soon as the shaft 26 has made its half revolution so as to bring the platen 20 to the limit of its initial movement, the shaft is automatically stopped as above described and at the same time the valve 76

is closed. The pump 61 then continues to operate, serving now to force oil through the pipes 60 and 62 into the cylinder for forcing the piston 19 upwardly for giving the platen 20 an additional movement toward the platen 22 at a very much slower speed and at a correspondingly very much greater effective pressure. As soon as the pressure of the platen 20 against the platen 22 through the interposed form and matrix 23 has reached the maximum desired, the pressure controlled device serves to open the switch 65 as above described for stopping the operation of the motor 63. Such stoppage may continue indefinitely by reason of the fact that the pressure is maintained substantially constant within the cylinder 16, or on the other hand, the motor may be successively started and stopped a number of times during the period through which it is desired to maintain the pressure upon the matrix between the platens. When the desired period of pressure at the desired degree of pressure has expired, the bell-crank lever 42 will be again moved downwardly by the operator for throwing the motor 36 into operation for giving the shaft 26 another half revolution for moving the platen 20 downwardly and serving as above described to open the switch 66 for throwing the motor 63 out of operation. At the start of this movement, the valve 76 is opened for permitting the oil to escape through the pipe 62, the pipe 75 and the valve 76 to the tank 59, serving to permit the platen 20 and its connected parts to descend quickly by gravity so as to be ready for the successive operation.

By the use of this improved mechanism, the desired heavy pressure can be applied upon the platen 20 at the end of the operative movement of the platen. At the same time, the platen 20 can be moved upwardly through the initial portion of its stroke at a comparatively rapid rate of movement whereby a very considerable amount of time is saved in the operation of the device. By the arrangement of valves and controls, the apparatus for giving the final operative movement to the platen 20 is in operation before the end of the initial movement of the platen so that no time whatever is lost at any stage of the operation.

Referring now to Figs. 6 and 7 which show a modified form of construction, the arrangement and construction are substantially the same except with respect to the means for actuating the piston and for controlling the operative stroke of the piston by which the platen is given its final operative movement. In this construction the parts are indicated by the same reference characters as those indicated above to the extent that the construction is the same.

In the construction of Figs. 6 and 7, a single motor 82 is provided for giving the platen both its initial quick movement and

its final operative movement toward the platen 22. This motor 82 is connected with the shaft 26 through the medium of a shaft 30, a worm 29 and a worm gear 28, but the 5 worm 29 is connected with the shaft 30 through the medium of a sleeve 83 and a clutch 84 rather than being connected directly as in the construction before described. The movable member of the clutch 84 is 10 moved into and out of operative clutching engagement by means of a lever 85 pivotally mounted between the shaft 30 and the operating rod 40, such lever 85 having a flexible connection with the rod 40 and the clutch so as 15 to throw the clutch into engagement when the rod 40 is moved toward the right in Fig. 6. The slow movement driving mechanism is connected with the motor 82 through the medium of a sprocket chain 86 connecting 20 sprockets 87 and 88 mounted respectively upon the shaft 30 and the shaft of the pump 61.

By the provision of the clutch 84 in the connections between the motor 82 and the shaft 26, I am enabled to stop the rotation of the shaft 26 without stopping the motor 82 so that the motor can continue to drive the pump 61 after the shaft 26 has been stopped at the end of its half revolution.

30 For controlling the motor 82, I have provided a system of line wires 89 leading from any suitable source of electrical energy and connecting the motor 82 in series with the switch 38. A second switch is connected in 35 parallel with the switch 38, such connection being effected by line wires 90. This second switch in parallel with the switch 38 is in the form of a commutator comprising a brass plate 91 and a fiber plate 92 mounted upon the shaft 26, brushes 93 being arranged to bridge across the plate 91 when the shaft 26 40 is in the position for holding the platen 20 in its uppermost position. Thus, when the switch 38 is opened at the end of the half 45 rotation of the shaft 26 by which the platen 20 is raised to its operative pressure position, the commutator switch is effective for continuing the circuit through the motor 82. When, however, the shaft 26 has been given 50 its successive half rotation for moving the platen 20 downwardly out of operative pressure position, the fiber plate 92 is then in position for engaging the brushes 93 and the motor 82 is consequently under the control of 55 the switch 38.

In the construction in Fig. 6, I have provided a different means for controlling the pressure. The motor 82 and the pump 61 are 60 permitted to run constantly during the time when the platen 20 is held in its uppermost position, but a relief valve 94 is provided as a by-pass between the pipe 60 and the tank 59 adapted to permit the oil to return to the tank 59 rather than to be forced into the cylinder

16 when the pressure has reached the desired 65 maximum. For regulating the pressure at which this by-pass action shall take place, the valve 94 is made adjustable, such valve being of any approved type such as is well known in the art.

When the form is placed in position between the platens 20 and 22, the motor 82 is started in the manner above described in connection with the motor 36, by a movement of the operating rod 40 toward the right in Fig. 7, serving to close the clutch 84 for giving the shaft 26 a half rotation, such shaft being thrown out of rotation at the end of the half revolution against the action of the spring 45 by the use of a cam 47 and cooperating mechanism as above described in connection with the other device. When the shaft 26 has reached the position as shown in Fig. 7, in which position the operating rod 40 is permitted to move toward the left in Fig. 6, the 80 clutch 84 is opened. At the same time the switch 38 is opened, but the motor 82 continues to operate by reason of the provision of the switch as shown in Fig. 7 which is then in the position as there shown. The pump 90 61 will, of course, have started operation at the same time when the motor 82 started, the oil taken from the tank 59 being permitted to pass into the cylinder 16 along with a much greater supply of oil passing at the same 95 time into the cylinder through the pipe 75 and the valve 76 as the piston 19 is moved upwardly by mechanical means through the action of the links 55. When the valve 76 closes at the end of the initial upward movement 100 of the platen 20, the pump is by such closure of the valve 76 rendered effective for forcing the oil into the cylinder beneath the piston for giving the platen 20 its final operative movement toward the platen 22 in the manner 105 before described. When the pressure has reached the desired maximum, the relief valve 94 operates. When the pressure has been maintained for the desired period of time against the form and matrix 23, the lever 42 is 110 again moved downwardly serving by the succeeding half revolution of the shaft 26 to restore the parts to their initial positions.

While the drawings show the top platen held stationary and the bottom platen only 115 movable, with the motor and its cooperating means located above the platens for applying power mechanically thereto, it will be understood that the invention is not limited to this construction, except as it may be so limited with respect to certain of the claims since some other arrangement might well be employed. Moreover, while the form of construction in other respects as illustrated is preferred, it is to be understood that the invention is not to be limited to the form as 120 shown except so far as the claims are specifically so limited, since it will be evident that

changes might well be made in the construction without departing from the invention.

I claim:

1. In a matrix forming machine, the combination of a frame, a platen mounted on said frame, a second platen movable on said frame toward and from said first named platen, a shaft revolubly mounted on said frame, means for driving said shaft, means actuated by a half rotation of said shaft for giving said second platen a predetermined initial movement toward said first named platen, automatically operating means for stopping the rotation of said shaft at the end of each half rotation thereof, and other means of comparatively much greater effective power for giving said second platen additional movement toward said first named platen for applying a heavy pressure thereon. 10
2. In a matrix forming machine, the combination of a frame, a platen mounted on said frame, a second platen movable on said frame toward and away from said first named platen, a shaft revolubly mounted on said frame, means for driving said shaft, means actuated by a half rotation of said shaft for giving said second platen a predetermined initial movement toward said first named platen, automatically operating means for stopping the rotation of said shaft at the end of each half rotation thereof, and other means of comparatively much greater effective power adapted automatically at the end of the initial movement of the second platen to give said second platen an additional movement toward said first named platen for applying a heavy pressure thereon. 20
3. In a matrix forming machine, the combination of a frame, a platen mounted on said frame, a second platen movable toward and from said first named platen, mechanically operated power means adapted on an operative stroke in one direction to apply pressure on said second platen for giving it a quick initial movement toward said first named platen and adapted on a stroke in the opposite direction very quickly to relieve said pressure, and hydraulically operated power means adapted after the initial movement of said second platen to give it an additional movement by the application of much heavier pressure thereto. 30
4. In a matrix forming machine, the combination of a frame, a platen mounted on said frame, a second platen movable toward and from said first named platen, mechanically operated power means for giving said second platen a quick initial movement toward said first named platen, mechanically operated means for throwing said power means out of operation at the end of a predetermined movement of the platen thereby, hydraulic power means for giving said second platen its final movement serving to apply heavy pressure on said first named 40
5. In a matrix forming machine, the combination of a frame, a platen mounted on said frame, a second platen movable on said frame toward and from said first named platen, a shaft revolubly mounted on said frame, links mounted eccentrically on said shaft and connected with said second platen adapted by the rotation of the shaft to move said second platen toward said first named platen, and other power means for applying a heavy final pressure from said second platen to said first named platen, said second platen being movable to a limited extent toward said first named platen with respect to said links. 50
6. In a matrix forming machine, the combination of a frame, a platen mounted on said frame, a second platen movable on said frame toward and from said first named platen, a shaft revolubly mounted on said frame, links mounted eccentrically on said shaft, connections between said links and said second platen for moving the platen toward said first named platen and arranged to permit said second platen to move to a limited extent toward said first named platen independently of the links, and other power means for applying a heavy final pressure from said second platen to said first named platen. 60
7. In a matrix forming machine, the combination of a frame, a platen mounted on said frame, a second platen movable on said frame toward and from said first named platen, a shaft revolubly mounted on said frame, links mounted eccentrically on said shaft, connections between said links and said second platen for moving the platen toward said first named platen and arranged to permit said second platen to move to a limited extent toward said first named platen independently of the links, and other power means acting directly upon said second platen independently of said links for applying a heavy final pressure on said second platen toward said first named platen. 70
8. In a matrix forming machine, the combination of a frame, a platen mounted on said frame, a second platen movable on said frame toward and from said first named platen, a shaft revolubly mounted on said frame, links mounted eccentrically on said shaft, connections between said links and said second platen for moving the platen toward said first named platen and arranged to permit said second platen to move to a limited extent toward said first named platen independently of the links, and hydraulic power means for applying a heavy final pressure directly on said second platen independently of said links. 80
9. In a matrix forming machine, the combination of a frame, a platen mounted on said 90

- frame, a second platen movable on said frame toward and from said first named platen, a shaft revolubly mounted on said frame, links mounted eccentrically on said shaft, connections between said links and said second platen for moving the platen toward said first named platen and arranged to permit said second platen to move to a limited extent toward said first named platen independently of the links, a cylinder mounted on said frame, a piston in said cylinder and arranged to press on said second platen toward said first named platen, and pressure means for operating said piston.
- 10 15 10. In a matrix forming machine, the combination of a frame, a platen mounted on said frame, a second platen movable on said frame toward and from said first named platen, a shaft revolubly mounted on said frame, links mounted eccentrically on said shaft, connections between said links and said second platen for moving the platen toward said first named platen and arranged to permit said second platen to move to a limited extent toward said first named platen independently of the links, a cylinder mounted on said frame, a piston in said cylinder and rigidly connected with said second platen, and pressure means for operating said piston.
- 20 25 30 35 40 45 50 55 60 65 11. In a matrix forming machine, the combination of a frame, a platen mounted on said frame, a second platen movable on said frame toward and away from said first named platen, a shaft revolubly mounted on said frame, means for driving said shaft, means actuated by a half rotation of said shaft for giving said second platen a predetermined initial movement toward said first named platen and adapted by the succeeding half rotation of the shaft to release said second platen for movement away from the first named platen, manually operated means for starting the rotation of said shaft, automatically operated means for stopping the rotation of the shaft at the end of each half rotation thereof, other means of comparatively much greater power for giving said second platen its final movement for applying heavy pressure on said first named platen, and means actuated by the movement of said first named power means for throwing said second named power means into and out of operation.
- 70 75 80 85 90 95 100 105 110 115 120 125 130 12. In a matrix forming machine, the combination of a frame, a platen mounted on said frame, a second platen movable on said frame toward and away from said first named platen, a shaft revolubly mounted on said frame, means for driving said shaft, means actuated by a half rotation of said shaft for giving said second platen a predetermined initial movement toward said first named platen and adapted by the succeeding half rotation of the shaft to release said second platen for movement away from the first named platen, manually operated means for starting the rotation of said shaft, automatically operated means for stopping the rotation of the shaft at the end of each half rotation thereof, hydraulic power means adapted to act directly upon said second platen for giving it its final movement for applying heavy pressure on said first named platen, and means actuated by the movement of said first named power means for throwing said second named power means into and out of operation.
13. In a matrix forming machine, the combination of a frame, a platen mounted on said frame, a second platen movable on said frame toward and away from said first named platen, a shaft revolubly mounted on said frame, means for driving said shaft, means actuated by a half rotation of said shaft for giving said second platen a predetermined initial movement toward said first named platen and adapted by the succeeding half rotation of the shaft to release said second platen for movement away from the first named platen, manually operated means for starting the rotation of said shaft, automatically operated means for stopping the rotation of the shaft at the end of each half rotation thereof, hydraulic power means adapted to act directly upon said second platen for giving it its final movement for applying heavy pressure on said first named platen, and means adapted upon the movement of said second platen toward said first named platen to throw said second named power means into operation and adapted upon the movement of the second platen away from the first named platen to throw said second named power means out of operation.
14. In a matrix forming machine, the combination of a frame, a platen mounted on said frame, a second platen movable on said frame toward and away from said first named platen, a motor, means driven by the motor for moving said second platen toward said first named platen for applying pressure on said first named platen, a second motor, means driven by said second motor for applying comparatively much greater effective power on said second platen for pressing on said first named platen, and means adapted automatically to start said second motor into operation before said platen reaches the end of its stroke under the influence of said first named motor.
15. In a matrix forming machine, the combination of a frame, a platen mounted on said frame, a second platen movable on said frame toward and away from said first named platen, a motor, means driven by the motor for moving said second platen toward said first named platen for applying pressure on said first named platen, hydraulic power means for applying comparatively much greater power on said second platen for pressing on said first named platen, an elec-

tric motor connected with said hydraulic power means for driving it, a switch arranged in the electrical connections for said electric motor, and means adapted automatically to close said switch for starting the second motor before said second platen reaches the end of its stroke under the influence of said first named motor.

16. In a matrix forming machine, the combination of a frame, a platen mounted on said frame, a second platen movable on said frame toward and away from said first named platen, a motor, means driven by the motor for moving said second platen toward said first named platen for applying pressure on said first named platen, a second motor, hydraulic power means driven by said second motor for applying comparatively much greater power on said second platen for pressing on said first named platen, means for starting said second motor into operation before said second platen reaches the end of its stroke under the influence of said first named motor, and means controlled by the pressure developed by said hydraulic power means for stopping and starting said second motor for keeping the pressure within certain predetermined limits.

17. In a matrix forming machine, the combination of a frame, a platen mounted on said frame, a second platen movable on said frame toward and away from said first named platen, a motor, means driven by the motor for moving said second platen toward said first named platen for applying pressure on said first named platen, hydraulic power means for applying comparatively much greater power on said second platen for pressing on said first named platen, an electric motor connected with said hydraulic power means for driving it, a switch arranged in the electrical connections for said electric motor, means for closing said switch for starting the second motor before said second platen reaches the end of its stroke under the influence of said first named motor, a second switch in the electrical connections of said electric motor, and means controlled by the pressure developed by said hydraulic power means for opening and closing said second switch for keeping the pressure within certain predetermined limits.

18. In a matrix forming machine, the combination of a frame, a platen mounted on said frame, a second platen movable on said frame toward and away from said first named platen, means for giving the second platen an initial movement toward said first named platen, a cylinder on said frame, a piston in said cylinder for giving said second platen an additional movement toward said first named platen for applying a heavy pressure thereon, a tank, a pipe leading from said tank to said cylinder, a pump interposed in said pipe between the tank and the cylinder, a second

pipe connecting said cylinder with said tank, a valve interposed in said second pipe through which the fluid returns from the pump to the tank when the valve is open and which serves to force the fluid from the pump into the cylinder when the valve is closed, and means controlled by the operation of said first named power means for moving said second platen toward said first named platen adapted to close said valve for rendering the pump effective for applying pressure on said second platen.

19. In a matrix forming machine, the combination of a frame, a platen mounted on said frame, a second platen movable on said frame toward and away from said first named platen, power means for giving said second platen a predetermined initial movement toward said first named platen, hydraulic power means for applying a heavy final pressure from said second platen to the first named platen, a valve by the closing of which said hydraulic power means is made effective on said second platen, and means actuated by the movement of said first named power means for closing said valve before said second platen reaches the end of its operative stroke under the influence of said first named power means.

20. In a matrix forming machine, the combination of a frame, a platen mounted on said frame, a second platen movable on said frame toward and away from said first named platen, means for giving the second platen an initial movement toward said first named platen, a cylinder on said frame, a piston in said cylinder for giving said second platen an additional movement toward said first named platen for applying a heavy pressure thereon, a valve by the closing of which said piston is made effective for moving said second platen, and means controlled by the operation of said first named power means for moving said second platen toward said first named platen adapted to close said valve.

21. In a matrix forming machine, the combination of a frame, a platen mounted on said frame, a second platen movable toward and from said first named platen, means for giving said second platen a quick initial movement toward said first named platen, hydraulic power means for giving said second platen its final movement serving to apply heavy pressure on said first named platen, and means controlled by the pressure for regulating the operation of said hydraulic power means.

22. In a matrix forming machine, the combination of a frame, a platen mounted on said frame, a second platen movable toward and from said first named platen, means for giving said second platen a quick initial movement toward said first named platen, hydraulic power means for giving said second platen its final movement serving to apply heavy

pressure on said first named platen, and means controlled by the pressure for throwing said hydraulic power means out of operation.

5 23. In a matrix forming machine, the combination of a frame, a platen mounted on said frame, a second platen movable toward and from said first named platen, means for giving said second platen a quick initial movement toward said first named platen, hydraulic power means for giving said second platen its final movement serving to apply heavy pressure on said first named platen, and means controlled by the pressure for 10 throwing said hydraulic power means successively into and out of operation for maintaining a certain predetermined pressure between said platens.

24. In a matrix forming machine, the combination of a frame, a platen mounted on said frame, a second platen movable toward and from said first named platen, means for giving said second platen a quick initial movement toward said first named platen, hydraulic power means for giving said second platen its final movement serving to apply heavy pressure on said first named platen, a motor for driving said hydraulic power means, and means controlled by the pressure 25 between said platens for starting and stopping said motor for maintaining a predetermined pressure.

25. In a matrix forming machine, the combination of a frame, a platen mounted on said frame, a second platen movable toward and from said first named platen, power means for giving said second platen a quick initial movement toward said first named platen, means for throwing said power means out of 30 operation at the end of a predetermined movement of the platen thereby, other power means for giving said second platen its final movement toward said first named platen for applying heavy pressure thereon, and automatically operating means for throwing said 35 second named power means into operation before the end of the operation of said first named power means.

26. In a matrix forming machine, the combination of a frame, a platen mounted on said frame, a second platen movable toward and from said first named platen, a reciprocatory

member, power means for driving said member alternately in opposite directions, means adapted upon a stroke of said member in one direction to apply pressure on said second platen for giving it a quick initial movement toward said first named platen and adapted upon a stroke in the opposite direction very quickly to relieve said pressure, and other power means adapted after the initial quick movement of said platen to give said platen an additional movement in the same direction by the application of comparatively much heavier pressure thereto. 40 45 60 65

27. In a matrix forming machine, the combination of a frame, a platen mounted on said frame, a second platen movable toward and from said first named platen, a reciprocatory member, power means for driving said member alternately in opposite directions, means adapted upon a stroke of said member in one direction to apply pressure on said second platen for giving it a quick initial movement toward said first named platen and adapted 70 upon a stroke in the opposite direction very quickly to relieve said pressure, and other power means thrown automatically into operation at substantially the end of the operative stroke of said first named power means for applying comparatively much heavier pressure to said second platen for completing its movement. 75 80

28. In a matrix forming machine, the combination of a frame, a platen mounted on said frame, a second platen movable toward and from said first named platen, a reciprocatory member, power means for driving said member alternately in opposite directions, means adapted upon a stroke of said member in one 85 direction to apply pressure on said second platen for giving it a quick initial movement toward said first named platen and adapted upon a stroke in the opposite direction very quickly to relieve said pressure, an electric 90 motor, means driven by said motor for applying comparatively much heavier pressure to said platen for completing its movement, and automatically operating means for throwing said motor into operation at substantially the 95 end of the operative stroke of said first named power means. 100

ERNEST JAMES SMITH.
